UNITED STATES PATENT OFFICE

1,926,153

HEEL-CHANNELING MACHINE

Norwood H. Knowlton, Rockport, Mass., assignor
to United Shoe Machinery Corporation, Paterson, N. J., a corporation of New Jersey

Application June 12, 1930, Serial No. 460,769,
and in Great Britain November 27, 1929

16 Claims. (Cl. 12—42)

This invention relates to machines for operating upon heels and is illustrated as embodied in a machine designed to form in the breasts of Louis heels channels for receiving the marginal 5 portions of heel covers.

In United States Letters Patent No. 1,704,204, granted on March 5, 1929 on application of William H. Nutt, there are described Louis heels having in their breasts cover-receiving channels or 10 slots located near the breast edges of the heels and extending substantially parallel thereto.

It is an object of the present invention to provide a machine for quickly and accurately forming in the breasts of heels cover-receiving channels 15 or slots such as are illustrated in the above-mentioned Letters Patent.

To this end and in accordance with a feature of the present invention, the illustrated machine is provided with a rotary disk cutter and gages 20 positioned at opposite sides of the cutter and constructed and arranged to engage the breast and a side respectively of a heel to position the heel relatively to the cutter for forming in the breast of the heel as the heel is moved past the cutter a heel-cover-receiving channel or slot.

In order properly to position the heel relatively to the cutter for forming in the breast of the heel a channel or slot positioned at a predetermined distance from a breast edge of the heel 30 and in order to control the depth of the channel, each of the illustrated gages is mounted for adjustment relatively to the cutter and is also mounted for movement relatively to the other. The illustrated gage which engages the side of the heel has a heel-engaging surface shaped to 35 accommodate heels of different sizes and styles and in accordance with a further feature of the invention is made of flexible material and is constructed and arranged to have the curvature of 40 its heel engaging surface controlled by the operator.

Referring to the drawings,

Fig. 1 is a front elevational view of a machine embodying the present invention;

45 Fig. 2 is a side elevational view of a portion of the right-hand channeling unit of the machine illustrated in Fig. 1 and shows in detail channeling and guiding instrumentalities for forming in the breast of a Louis heel moved past 50 the channeling unit a channel which is positioned near one of the breast edges of the heel and extends substantially parallel thereto;

Fig. 3 is a plan view of the right-hand channeling unit illustrated in Fig. 1;

55 Fig. 4 is a sectional view of the channeling unit

illustrated in Fig. 3, the section being taken along the line IV—IV of Fig. 3;

Fig. 5 is a detail view showing the relative positions of a heel and heel-guiding and heel-channeling instrumentalities during the channeling 60 operation; and

Fig. 6 is a perspective view of a heel the breast of which has been channeled in the above-illustrated machine.

The illustrated machine comprises a rotary 65 cutter 20 for forming in the breast of a Louis heel 24 (Fig. 6) heel-cover-receiving channels or slots 26 which are substantially parallel to the breast edges 28 of the heel and are of uniform depth throughout a considerable portion of their 70 length as the heel is moved past the cutter 20 by the operator, a gage 30, and a rest or gage 32 adapted to engage the breast and a side of the heel (Fig. 5) respectively for positioning the heel relatively to the cutter. 75

It will be noted that the illustrated machine includes right and left units A and B (Fig. 1) respectively for operating upon the heels, which units are duplicates of each other except in so far as their parts are reversed in order that the operator may feed the heel without reversing it in the same general direction as he channels opposite sides of the heel breast. It will therefore be necessary to describe but one of these units, the reader keeping in mind that the other unit has 85 a reversed but corresponding element.

The operating parts of the machine are supported upon a standard 34 (Fig. 1) carrying upstanding brackets 36 upon the upper and lower 90 parts of each of which are mounted housings 38, 40 respectively. Journaled in each of the housings 38 is a shaft 42 (Fig. 4) to which one of the above-referred-to cutters 20 for forming channels 26 is secured, and journaled in each of the housings 40 is a shaft 44 upon which is mounted 95 a cutter 46 for chamfering the inner breast edges 48 at the upper part of the breast of the heel. The chamfering units form no part of this invention and are not claimed in this application but are fully described and claimed in United 100 States Letters Patent No. 1,854,263, granted April 19, 1932, on an application filed in my name. It will therefore be unnecessary further to describe the chamfering mechanism in this application.

The inner end of each of the shafts 42 (Fig. 4) is provided with a bore 50 into which a barrel portion 52 of the cutter 20 fits, each of the shafts 42 and its respective cutter 20 being clamped together for rotation by a screw 54 carried by a bushing 56 mounted upon each of the bored por- 110

tions 50 of the shafts. The shafts 42 are illustrated as being operated by belts 58 which are driven by motors controlled by hand switches 60 (Fig. 1).

5 In order to position the heel relatively to the rotary cutter 20 as the operator moves the same past the cutter to form the channel 26, the machine is provided with the gage 30 and the gage 32 above referred to, the former of which is 10 located adjacent to and in front of the rotary cutter 20 for engaging the breast of the heel and the latter of which is positioned behind the rotary cutter 20 for engaging one of the sides of the heel adjacent to a breast edge 28 thereof. The 15 gages 30 and 32 are supported from a casing 62 bolted to the housing 38 and having a recessed portion 64 through which the shaft 42 passes. The gage 30 which engages the breast 20 of the heel and cooperates with the gage 32 in supporting the heel relatively to the cutter 20 also regulates the depth of the cut and is conveniently adjusted in a vertical direction (Figs. 2 and 4) by a screw 66 carried by a bracket 68 and having a circumferentially disposed slot 70 25 for receiving a flanged end portion 72 of the gage 30. The gage 30 is normally rigidly clamped to the bracket 68 by a set-screw 74 carried by the bracket and passing through a slot 76 in the gage 30 but may be conveniently turned from clamping 30 position in order that the required vertical adjustment may be effected by the screw 66. Provision is also made for moving the gage 30 in a horizontal plane and transversely of as well as lengthwise of the shaft 42 in order effectively to 35 position the heel relatively to the cutter as will now be described. The bracket 68 is provided with a channel 78 for receiving a tongue 80 of a carrier 82 which is mounted for sliding movement in a guideway 84 of a collar 86 secured to the casing 62 by set-screw 88. A combined adjusting screw and clamp 90 in threaded engagement with the carrier 82 and passing through a slot in the bracket 68 controls the horizontal 40 adjustment of the gage 30 transversely of the shaft 42 and a screw 92 carried by the collar 86 and passing through a slot 94 in the carrier 82 is utilized to adjust the gage 30 lengthwise of the shaft 42.

45 The gage 32 against which the portion of the side of the heel adjacent to one of the breast edges 28 is engaged is deformable and comprises a strip of flexible material secured to a supporting arm 96 by a rivet 98. The arm 96 is normally secured to a bracket 100 but may be adjusted relatively thereto in a direction indicated by the arrows 102 through a screw-and-slot connection 104, the bracket 100 being adjustably supported for movement lengthwise of the shaft upon the collar 86 by utilizing a screw-and-slot 50 connection 106.

55 In order to flex the gage 32 for accommodating different sizes and shapes of heels, the machine is provided with a pair of depending arms 108 between the enlarged portions 110 of which the sides 112 of the gage 32 are positioned (Fig. 2). The arms 108 are bolted to a U-shaped bracket 114 having a housing 116 secured thereto by screws 118. The housing is constructed and arranged to receive a rectangular rod 120 attached to a lug 122 bolted to the collar 86 and along which rod the bracket 114 is guided as will now be described. In order to move the housing 116 together with the bracket 114 along the rod 120 for changing the curvature of the engaging portion of the gage 32, the housing carries in thread-

ed relation therewith an elongated screw 124 having an enlarged head 126, the lower face 128 of which engages against the outer end 130 of the rod 120. The gage 32, when flexed (Fig. 3), normally tends to move the U-shaped bracket 114 and the housing 116 toward the cutter 20 until the head 126 of the screw 124 engages the end 130 of the rod 120, the curvature of the gage 32 being changed by turning the screw 124, thereby moving the U-shaped bracket 112 and its depending arms 106 toward or away from the cutter. In forming channels 26 in the breasts of heels, the operator proceeds as follows: after the gages 30 and 32 have been properly positioned relatively to the cutter 20 for guiding the heel past the cutter and to form a channel of the required depth and curvature in the breast of the heel and after the engaging surface of the gage 32 has been adjusted to accommodate heels of the size and style to be operated upon, the operator moves the heel past the channeling means, the heel being guided by the gages 30 and 32 as illustrated in Fig. 5. It is customary for the operator to start at the tread end of the heel and to cut progressively toward the upper part of the heel, the channel along the right breast edge being formed in unit A and the channel along the left breast edge being formed in unit B. The direction of movement of the heel past the cutter during the trimming operation may be 105 changed, however, if desired, so as to start the cut at the attaching face of the heel and to cut progressively toward the tread face.

110 In order that the operator will not be subjected to dust during the channel-forming operation, the illustrated machine is provided with a dust hood 132 having an opening 134 disposed immediately above each of the channeling units A and B, and for cleaning out the channels where it is 115 found to be necessary, the machine is provided with a stiff brush 136 mounted for rotation upon a shaft 138.

120 Having thus described my invention, what I claim as new and desire to secure by Letters Patent of the United States is:

1. A machine for operating upon heels having, in combination, a disk cutter, a gage positioned at one side of the cutter and constructed and arranged to engage a breast of a heel, and another gage positioned at the other side of the cutter and constructed and arranged to engage a side of the heel and to cooperate with the first-named gage in guiding the heel past the cutter to form in the breast of the heel a heel-cover-receiving slot extending heightwise of the heel, said first-named gage being adjustable relatively to the cutter and to the second-named gage for varying the depth of the slot formed in the breast of the heel.

125 2. A machine for operating upon heels having, in combination, a rotary disk cutter, a gage constructed and arranged to engage the breast of a heel, and another gage constructed and arranged to engage a side of the heel and to cooperate with the first-named gage in guiding the heel past the cutter to form in the breast of a heel a heel-cover-receiving slot extending parallel to a heel-breast edge formed between said side and the breast of the heel, said first-named gage being 130 adjustable relatively to the cutter radially of the axis of rotation of the cutter to vary the depth of the slot and said second-named cutter being adjustable independently of the first-named gage 135 radially as well as axially of the axis of rotation 140

- of the cutter to vary the distance of the slot from said breast edge of the heel.
3. A machine for slotting heels having, in combination, a rotary cutter, a gage for engaging the breast of a heel, and a gage for engaging a side of the heel, said gages having heel-engaging surfaces positioned at opposite sides of the rotary cutter and constructed and arranged to position the heel relatively to the cutter for forming in the breast of the heel as it is moved past the cutter a cover-receiving slot which is substantially parallel to one of the breast edges of the heel.
4. A machine for slotting heels having, in combination, a rotary disk cutter, a gage for engaging the breast of a heel, and a gage for engaging a side of the heel, said gages having heel-engaging faces positioned respectively at opposite sides of and adjacent to the cutter and being constructed and arranged to position the heel relatively to the cutter for forming in the breast of the heel as the heel is moved past the cutter a relatively deep and narrow heel-cover-receiving slot which is located adjacent to one of the breast edges of the heel and extends substantially parallel to said edge.
5. A machine for slotting heels having, in combination, a rotary disk cutter, a gage constructed and arranged to engage the breast of a Louis heel, and a gage comprising a cylindrical surface inclined to the plane of rotation of the cutter and constructed and arranged to engage a side of the heel, said gages being positioned at opposite sides of and adjacent to the cutter and being constructed and arranged to position the heel relatively to the cutter for forming in the breast of the heel as the heel is moved past the cutter a relatively deep and narrow heel-cover-receiving slot which is located adjacent to one of the breast edges of the heel and extends substantially parallel to said edge.
6. A machine for slotting heels having, in combination, a cutter, a gage for engaging the breasts of heels, and a gage having a heel-engaging face the shape of which may be changed for engaging portions of the sides of heels of different shapes, said gages being constructed and arranged to position the heel relatively to the cutter for forming in the breast of the heel as the heel is moved past the cutter a heel-cover-receiving slot.
7. A machine for channeling heels having, in combination, a rotary cutter, a gage for engaging the breast of the heel, a deformable gage having a surface for engagement with a heel limited to a portion of the side of the heel adjacent to the edge formed by the junction of the heel breast and said side of the heel, said gages being constructed and arranged to position the heel relatively to the cutter for forming in the breast of the heel as the heel is moved past the cutter a heel-cover-receiving channel which is substantially parallel to said edge, and means for varying the curvature of the heel-engaging surface of the deformable gage.
8. In a heel-slotting machine, a rotary cutter, a gage for engaging the breasts of heels, and a gage having a heel-engaging face the shape of which may be changed, said gages being constructed and arranged to position the heels relatively to the cutter for forming in the breasts of the heels as the heels are moved past the cutter relatively deep and narrow heel-cover-receiving slots which are located adjacent to one of the breast edges of the heels and extend substantially parallel to said edges.
9. In a heel-slotting machine, a rotary cutter, a gage for engaging the breast of a heel, and a gage having a heel-engaging face the shape of which may be changed, said gages being constructed and arranged to position the heels relatively to the cutter for forming in the breast of the heel, as the heel is moved past the cutter, a relatively deep and narrow heel-cover-receiving slot which is located adjacent to one of the breast edges of the heel and extends substantially parallel to said edge and which is also of uniform depth throughout substantially its length.
10. In a heel-channeling machine, a cutter, a gage, a deformable gage, said gages being constructed and arranged to engage the breast and the side of a heel respectively to form in the breast of the heel as the heel is moved past the cutter a relatively deep and narrow heel-cover-receiving channel which is located adjacent to one of the breast edges of the heel and extends substantially parallel to said edge, and means to vary the curvature of the heel-engaging surface of the gage.
11. A machine for slotting heels having, in combination, a rotary cutter, gages positioned at opposite sides of the cutter, said gages being constructed and arranged to engage the breast and a side respectively of a heel for positioning the heel relatively to the cutter thereby forming in the breast of the heel, as the heel is moved past the cutter, a heel-cover-receiving slot which is substantially parallel to one of the breast edges of the heel, and means for adjusting the gage which engages the breast of the heel radially of the cutter to regulate the depth of the slot.
12. In a heel-slotting machine, a rotary cutter, gages, said gages being constructed and arranged to engage the breast and a side respectively of a heel for positioning it relatively to the cutter to form in the breast of the heel as the heel is moved past the cutter a heel-cover-receiving slot which is substantially parallel to one of the breast edges of the heel, and means for adjusting the gage, which engages the breast of the heel, radially of the cutter to regulate the depth of the slot, the gage which engages the side of the heel being adjustable axially of the cutter for regulating the distance of the slot from said breast edge.
13. In a machine for operating upon heels, a rotary cutter, a gage for engaging the breast of a heel, and a gage for engaging a side of the heel, said gages being positioned at opposite sides of the cutter and being constructed and arranged to position the heel relatively to the cutter for forming in the breast of the heel as the heel is moved past the cutter a heel-cover-receiving slot which is substantially parallel to one of the breast edges of the heel and which is of uniform depth throughout substantially its length, the first-named gage being adjustable relatively to the cutter to regulate the depth of the slot, and the second-named gage being adjustable relatively to the cutter for regulating the distance of the slot from said breast edge.
14. A machine for operating upon the heel of a shoe having, in combination, a rotary cutter for forming a heel-cover-receiving channel in the breast of said heel, a gage constructed and arranged to engage the breast of the heel, a deformable gage having a surface for engaging a side of the heel and constructed and arranged to cooperate with the gage accurately to locate the heel relatively to the cutter, means to vary the curvature of the heel-engaging surface of the deformable gage for accommodating heels of different sizes.

ferent sizes and styles, and means for adjusting the heel-breast-engaging gage relatively to the cutter to regulate the depth of the channel.

15. A machine for operating upon a heel of a shoe having, in combination, a rotary cutter to form a heel-cover-receiving channel in the breast of said heel, a gage constructed and arranged to engage the breast of the heel, a deformable gage having a surface constructed and arranged to engage the heel and limited to a portion of a side of the heel adjacent to the edge formed by the junction of the heel breast and said side of the heel, said gages being constructed and arranged to position the heel relatively to the cutter to form in the breast of the heel as it is moved past the cutter a heel-cover-receiving channel substantially parallel to said edge of the heel, means for varying the curvature of the heel-engaging surfaces of the gage for accommodating heels of different sizes and styles, means for adjusting the first-named gage relatively to the cutter to regu-

late the depth of the channel, and means for adjusting the second-named gage relatively to the cutter for regulating the distance of the channel from said edge.

16. In a heel-slitting machine, a cutter, a gage for engaging the breast of a heel, a gage for engaging a side of the heel, said gages being constructed and arranged to position the heel relatively to the cutter for forming in the breast of the heel as the heel is moved past the cutter a heel-cover-receiving slot which is located adjacent to one of the breast edges of the heel and extends substantially parallel to said edge, said second-named gage being adjustable relatively to the cutter for varying the distance of the slot from said edge and having a heel-engaging portion the curvature of which may be changed to approximate the curvatures of the sides of the different sizes and styles of heels.
